CLAIM

The ornamental design of an emergency working light, as shown and described.

DESCRIPTION

FIG. 1 is a left side elevation view with the lighting compartment in the open position.

FIG. 2 is a front elevation view thereof.

FIG. 3 is a rear elevation view thereof.

FIG. 4 is a right side elevation view with the lighting compartment in the open position.

FIG. 5 is a top plan view thereof.

FIG. 6 is a bottom plan view thereof.

FIG. 7 is a top plan view showing the lighting compartment rotated 90° counter clockwise along a vertical axis.

FIG. 8 is a left side elevation view showing the lighting compartment rotated along a horizontal axis; and,

FIG. 9 is a left side elevation view showing a fully unfolded position.
